Primary Examiner — Vy N Koenig(74) *Attorney, Agent, or Firm* — Womble Bond Dickinson (US) LLP(57) **CLAIM**

The ornamental design for a carrier, as shown and described.

DESCRIPTION

FIG. 1 is a perspective view of a carrier showing my new design.

FIG. 2 is a front elevation view of the carrier of FIG. 1, the rear elevation view is a mirror image.

FIG. 3 is a left elevation view of the carrier of FIG. 1, the right elevation view is a mirror image.

FIG. 4 is a top plan view of the carrier of FIG. 1.

FIG. 5 is a bottom plan view of the carrier of FIG. 1; and, FIG. 6 is a plan view of the carrier of FIG. 1 shown in an unfolded configuration.

All evenly-spaced broken lines depict environmental subject matter and form no part of the claimed design.
